CLAIM

The ornamental design for a coat rack, as shown and described.

DESCRIPTION

FIG. 1 is a top plan view of a coat rack showing my new design;

FIG. 2 is a bottom plan view thereof;

FIG. 3 is a front elevational view thereof on a reduced scale showing the rack in its fully extended state;

FIG. 4 is a rear elevational view of FIG. 3;

FIG. 5 is a right side elevational view of FIG. 3;

FIG. 6 is a left side elevational view of FIG. 3;

FIG. 7 is a front elevational view showing the coat rack in its fully contracted state;

FIG. 8 is a rear elevational view of FIG. 7;

FIG. 9 is a right side elevational view; and,

FIG. 10 is a left side elevational view of FIG. 7.

The broken line showing of hook fixtures in FIGS. 1-10 is for illustrative purposes only and forms no part of the claimed design.
